DESIGN FOR A CHENILLE NEGLIGEE

Murray M. Taradash, Fall River, Mass.

Application March 19, 1940, Serial No. 91,052

Term of patent 3½ years

To all whom it may concern:

Be it known that I, Murray M. Taradash, a citizen of the United States, residing at Fall River, in the county of Bristol and State of Massachusetts, have invented a new, original, and ornamental Design for a Chenille Negligee, of which the following is a specification, reference being had to the accompanying drawing, constituting a part thereof.

Fig. 1 is a front view of the chenille negligee showing my new design; and

Fig. 2 is a rear view of the chenille negligee shown in Fig. 1.

I claim:

The ornamental design for a chenille negligee, substantially as shown.

MURRAY M. TARADASH.
